United States Patent Office

Des. 211,222
Patented May 28, 1968

211,222

DISPLAY STAND

Joseph J. Trogan, 904 S. Michigan Ave.,
Saginaw County, Mich. 48602

Original design application Oct. 23, 1965, Ser. No. 87,844, now Patent No. 207,284, dated Mar. 28, 1967. Divided and this application Dec. 15, 1966, Ser. No. 5,054

Term of patent 14 years

(Cl. D80—9)

Fig 2

This is a division of design application Ser. No. D. 87,844, filed Oct. 23, 1965, now Design Patent No. D. 207,284.

I claim:

The ornamental design for a display stand, as shown and described.
